US0D1068098S

(12) **United States Design Patent** (10) Patent No.: **US D1,068,098 S**
(45) Date of Patent: ** Mar. 25, 2025

(54) **ATTACHMENT FOR MASSAGE DEVICE**

(71) Applicant: **Therabody, Inc.**, Los Angeles, CA (US)

(72) Inventors: **Jaime Sanchez Solana**, Los Angeles, CA (US); **Eduardo Merino**, Los Angeles, CA (US); **Zenger Zhou**, Shenzhen (CN); **Lymond Lin**, Shenzhen (CN); **Alex Zhu**, Xiamen (CN)

(73) Assignee: **Therabody, Inc.**, Los Angeles, CA (US)

(**) Term: **15 Years**

(21) Appl. No.: **29/933,718**

(22) Filed: **Mar. 21, 2024**

Related U.S. Application Data

(63) Continuation of application No. 29/910,763, filed on Aug. 24, 2023, now Pat. No. Des. 1,019,974.

CLAIM

The ornamental design for an attachment for massage device as shown and described.

DESCRIPTION

FIG. 1 is a top front isometric view of an attachment for massage device showing the claimed design;
FIG. 2 is a bottom front isometric view thereof;
FIG. 3 is another top front isometric view thereof;
FIG. 4 is a front elevation view thereof;
FIG. 5 is a rear elevation view thereof;
FIG. 6 is a left side elevation view thereof;
FIG. 7 is a right side elevation view thereof;
FIG. 8 is a top plan view thereof; and,
FIG. 9 is a bottom plan view thereof.

The broken lines in the figures show portions of the attachment for massage device that form no part of the claimed design.
